UNITED STATES PATENT OFFICE.

GEORGE M. MILLS, OF PHILADELPHIA, PENNSYLVANIA.

DESIGN FOR STICK-CANDY.

Specification forming part of Design No. **11,173**, dated April 29, 1879; application filed September 18, 1878.
[Term of patent 7 years.]

To all whom it may concern:

Be it known that I, GEORGE M. MILLS, of Philadelphia, in the county of Philadelphia and State of Pennsylvania, have invented a certain new and useful Design for Stick-Candy; and I do hereby declare the following to be a full, clear, and exact description of the invention, such as will enable others skilled in the art to which it pertains to make and use it, reference being had to the accompanying drawings, which form part of this specification, in which—

Figure 1 is an elevation, and Figs. 2 and 3 are, respectively, an end view and cross-section, of my design.

My design is plainly shown in said drawings; and consists, as will be observed therein, of an elongated cylindrical figure, B, having angular spiral grooves cut in its periphery or sides, so that an end view or cross-section will show a star, the ribs b in Fig. 1 or elevation having sharp edges b^2 , which said ribs in the other figures form the points of the star.

In the twisted stick the inner angles formed

at the base of the grooves appear, as well as the edges of the ribs.

What I claim as my invention is—

1. The design for stick-candy herein shown and described, consisting of a cylindrical figure spirally grooved or fluted, forming sharp-edged ribs, appearing in plan and cross-section as a star, the sides of said ribs forming sharp angles on the edges of and between the ribs, the inner angles being exposed, as shown.

2. The design for stick-candy, consisting of a cylindrical figure spirally grooved or fluted, forming sharp-edged ribs and sharp-angled grooves, and having the shape, in cross-section, of a six-pointed star, as shown and described.

In testimony that I claim the foregoing I have hereunto set my hand this 2d day of September, 1878.

GEORGE M. MILLS.
